UNITED STATES PATENT OFFICE.

CHARLES S. BEEBE, OF RACINE, WISCONSIN.

TWO-WHEELED VEHICLE.

SPECIFICATION forming part of Letters Patent No. 281,434, dated July 17, 1883.

Application filed November 6, 1882. (No model.)

To all whom it may concern:

Be it known that I, CHARLES S. BEEBE, of Racine, in the county of Racine and State of Wisconsin, have invented certain new and useful Improvements in Road-Carts; and I do hereby declare that the following is a full, clear, and exact description thereof.

My invention relates to two-wheeled vehicles, and will be fully described hereinafter.

10 In the drawings, Figure 1 is a side view of my device with one of the wheels removed. Fig. 2. is a perspective view of the gear with the body and wheels removed, and Fig. 3 is a detail.

15 A is the axle, to which are clipped the thills B. C is a cross-bar, connecting the thills in front of the axle.

20 D are springs, which are clipped at one end to the axle by shackles d, as shown in small detail, Fig. 3, and which extend up to the cross-bar C, and are shackled to it, as at c.

25 E are spring-bars, the inner ends of which rest upon springs D, and are clipped to them near cross-bar C, and the outer ends of bars E are connected by a semi-elliptic spring, F. The front end or foot board of the body G is pivoted to the cross-bar C in any suitable manner, and its rear or seat portion rests upon and is secured to spring F.

30 I may use any style of body, and may hang it in front by any means that will permit it to rise and fall as the springs yield, and I may hang the springs D to the axle and cross-bar by clips, shackles, or any other suitable connection without departing from the spirit of my invention.

35 My road-cart, besides being cheap and dura-

ble, is comfortable to ride in, as the jar incidental to riding over rough roads is greatly modified, first, by the springs D, as they transmit it to the spring-bars E, and they in turn still further modify it before it reaches the spring F. Therefore there can be no such sudden jerking action in my device when a corner is turned suddenly or an obstruction 45 is passed over, as is common in road-carts of other constructions.

What I claim as my invention, and desire to secure by Letters Patent, is—

1. The combination of springs extending 50 from the cross-bar to the axle, with spring-bars E, semi-elliptic spring F, uniting said spring-bars at their rear ends, and the body G, having seat portion resting upon and secured to the spring F, and front end or foot 55 board suspended from the cross-bar and adapted to rise and fall as the springs yield, substantially at set forth.

2. In a road-cart, the combination of axle A, thills B, cross-bar C, and springs D, extending between and suspended from beneath said axle and cross-bar, with the spring-bars E, spring F, connecting the rear ends of said bars, and body G, suspended from the cross-bar at its front and resting on the spring F at its 60 rear end, substantially as set forth.

In testimony that I claim the foregoing I have hereunto set my hand, on this 12th day of October, 1882, in the presence of two witnesses.

CHAS. S. BEEBE.
